UNITED STATES PATENT OFFICE

FRIEDRICH LUTZ, OF STUTTGART, GERMANY, ASSIGNOR TO UNION SPECIAL MASCHINENFABRIK, G. M. B. H., OF STUTTGART, GERMANY

BED STRUCTURE FOR SEWING MACHINES

Application filed June 28, 1928, Serial No. 288,830, and in Germany November 22, 1927.

The invention relates to new and useful improvements in sewing machines, and more particularly to the bed structure in the machine.

5 An object of the invention is to provide an integral bed structure within which the actuating shaft and the actuated parts beneath the plane of the cloth plate are mounted, and on which the overhanging arm with 10 the actuated parts therein is mounted.

A further object of the invention is to provide a supporting bed structure of the above type wherein the sides of the bed structure extend upwardly to substantially the plane 15 of the cloth plate and the ends of the bed structure are substantially open for the purpose of permitting the assembling of the parts and for giving access to the stitch forming elements beneath the cloth plate.

20 These and other objects will in part be obvious and will in part be hereinafter more fully disclosed.

In the drawings:—

Fig. 1 is a sectional view through the improved supporting bed structure with all parts removed therefrom.

Fig. 2 is a sectional view on the line 2—2 of Fig. 1.

Fig. 3 is a sectional view on the line 3—3 30 of Fig. 1.

Fig. 4 is a vertical sectional view longitudinally through the supporting bed and also through the overhanging arm mounted thereon.

35 The invention relates to a sewing machine and more particularly to the supporting bed structure which is preferably cast in one piece. Said bed structure includes a bottom portion from which rise integral side walls.

40 The side walls and bottom portion make up a frame structure which is substantially U-shaped in cross section and open at the top. There is an integral cross partition having a bearing for the main actuating shaft which 45 is located within the supporting bed structure and well beneath the upper edges of the side walls of the bed structure. The actuated parts usually present in a sewing machine and located beneath the cloth plate are 50 all mounted within this supporting bed struc-

ture. The supporting bed structure is substantially open at both ends as well as at the top and this permits the assembling of the parts. Detachably mounted on this supporting bed structure is an overhanging arm carrying a needle bar and means for actuating the needle bar. These parts are actuated by suitable connection with the actuating shaft in the supporting bed structure.

55 Referring more in detail to the drawings: 60 The supporting bed structure includes a body portion 1 having a bottom portion 2 extending from front to rear of the machine. Extending upwardly from the bottom portion are two side walls 3 and 4. These side walls 65 are formed integral with the bottom portion. As a matter of fact, the entire bed structure is one integral cast structure. As clearly shown in Fig. 2, the bed structure is 70 U-shaped in cross section with the upper part open. There is a cross partition 5 having a bearing 6 formed therein. The right hand end of the bed structure as viewed in Fig. 1 is partially closed by a cross partition 6^a which is formed with a large circular 75 opening 7.

80 The main actuating shaft is indicated at 8. This main actuating shaft is provided with a crank 9 and with suitable devices for operating the looper mechanism and the feeding mechanism. The opening 7 in the bed structure is of sufficient size to permit the shaft 8 with the eccentric member thereon to be inserted therethrough. A bearing sleeve 10 closes the circular opening 7 and 85 forms a very durable supporting bearing for the shaft 8.

85 The shaft 8 is driven by a suitable belt wheel 11. The looper is indicated at 12. The end of the supporting bed adjacent the 90 looper 12 is closed by a detachable cover plate 13. The throat plate of the machine is secured to the bed as indicated at 14. The fabric rests on this throat plate while it is being stitched. Working through the throat plate is a feed dog 15 which is operated for 95 feeding the material transversely across the supporting bed. This throat plate 14 is directly mounted on the supporting bed. The supporting bed is closed in part by a cover 100

plate 16 which is provided with a leaf spring 17 adapted to extend beneath the throat plate and a latch bolt 18 which evenly engages the recess 19 in the supporting bed.

5 Mounted on the supporting bed is an overhanging arm 20. The needle bar 21 reciprocates in the free end of the overhanging arm and carries a needle 22. The needle bar is reciprocated by a needle lever 23 which is 10 operated by a link 24 cooperating with the crank 9 in the main actuating shaft. The lever 23 is pivoted intermediate its ends as indicated at 25. This overhanging arm is detachably secured to the supporting bed 15 by screws 26.

All the parts may be assembled in the overhanging arm and it may then be attached to the supporting bed. Access to the screws can be had through the removable cover 20 plate 27. The attaching of the overhanging arm to the supporting bed accomplishes the closing of the upper portion of the supporting bed.

From the above it will be apparent that I 25 have provided a very durable supporting bed in which the actuated parts beneath the cloth plate are housed and supported. The actuating shaft is also located in this supporting bed which is one integral structure 30 and which is comparatively free from vibration. The parts may be readily assembled in this supporting bed and by the placing of the cover plates the parts are all substantially housed and yet readily accessible.

35 The overhanging arm, as noted above, may have its parts assembled therein after which it is attached to the supporting bed. Inasmuch as the overhanging arm is readily detachable, other overhanging arms may be 40 substituted therefor and thus sewing machines having different characteristics built on the same supporting bed. The overhanging arm is attached directly to the supporting bed and this forms a very durable sup- 45 port for the overhanging arm.

It is obvious that minor changes in the details of construction and the arrangement of parts may be made without departing from the spirit of the invention as set forth 50 in the appended claim.

Having fully described my invention, what I claim as new and desire to secure by Letters Patent, is:—

A sewing machine including a supporting 55 bed structure having integral side walls with its ends substantially open, a throat plate mounted at one end of said bed structure, an overhanging arm mounted at the other end of said bed structure, a cover plate between 60 the throat plate and the overhanging arm, a main actuating shaft located in said supporting bed and having an eccentric member mounted thereon, said opening in the bed structure adjacent the overhanging arm 65 being of sufficient size to permit the shaft

with the eccentric member thereon to be inserted therethrough, a sleeve for closing said opening and having a bearing for said shaft, and a cover plate for closing the other end of said supporting bed.

70 In testimony whereof, I affix my signature.
FRIEDRICH LUTZ.
